LOUNGING SOCK

Milton A. Wilson, Auburn, Wash.

Application May 5, 1953, Serial No. 24,866

Term of patent 14 years

(Cl. D7—7)

To all whom it may concern:

Be it known that I, Milton A. Wilson, a citizen of the United States of America, residing at Auburn, in the county of King and State of Washington, have invented a new, original, and ornamental Design for a Lounging Sock, of which the following is a specification, reference being had to the accompanying drawings, forming part thereof.

Fig. 1 is a fragmentary perspective view of a lounging sock showing my new design.

Fig. 2 is a fragmentary side elevation of the same.

Fig. 3 is a fragmentary rear view of the same.
Fig. 4 is a side elevation of the complete lounging sock.

I claim:

The ornamental design for a lounging sock, as shown.
